CLAIM

The ornamental design of an instrument for diagonal observation by microscope, as shown and described.

DESCRIPTION

FIG. 1 is a front elevational view of an instrument for diagonal observation by microscope showing my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;
FIG. 7 is a sectional view taken along line VII—VII in FIG. 1;

FIG. 8 is a perspective view which illustrates the instrument mounted in association with a microscope, the latter being shown by broken lines for illustrative purposes only and forming no part of the claimed design; and

FIG. 9 is a right side elevational view similar to FIG. 6 illustrating a different operational state.

FIG. 1

FIG. 2

FIG. 3

FIG. 4

FIG. 6

FIG. 5

FIG. 7

FIG. 8

FIG. 9
